OIL BURNER CONTROL

Everett H. White, St. Paul, Minn.

Application September 21, 1933, Serial No. 690,396

3 Claims. (Cl. 158—28)

The present invention has relation to an oil burner control.

An object of the invention is to provide an oil burner control wherein will be incorporated various improved features and characteristics of construction novel both as individual entities of said oil burner control and in combination.

A further object is to provide an oil burner control which, in its entirety, except for the room 10 thermostat, or equivalent, the ignition device, motor, and valve for said control, and certain electrical wiring, which parts must of necessity be elsewhere, may be housed as a single unit capable of easy and practicable removable assembly with the stack of an oil burner furnace.

A further object is to provide in the oil burner control, a stack thermostat of novel and improved construction adapted to manipulate various electric switches of said control in novel and im- 20 proved manner.

A further object is to provide in the oil burner control, a room thermostat, or equivalent, including a permanent magnet the functions of which are to firmly hold said contact elements 25 in engagement when once together and thus provide a regulatable differential for the smooth and proper operation of the oil burner control, and to provide a quick and snappy make and break of the switch of said room thermostat.

And a still further object is to provide an oil 30 burner control wherein the ignition device, the motor, and the valve when employed, are adapted to be connected in line wire circuits of relatively high voltage, while all of the other electricity 35 conveying parts of said control, including the switches manipulated by the stack thermostat, are adapted to be connected in circuits of relatively low voltage including the stepped-down secondary of a transformer associated with said 40 line wires.

With the above objects in view, as well as others which will appear as the specification proceeds, the invention comprises the construction, arrangement and combination of parts as now to be 45 fully described and as hereinafter to be specifically claimed, it being understood that the disclosure herein is merely illustrative and intended in no way in a limiting sense, changes in details of construction and arrangement of parts being 50 permissible so long as within the spirit of the invention and the scope of the claims which follow.

In the accompanying drawings forming a part of this specification,

Fig. 1 is a vertical sectional view of an oil burner 55 control made according to the principles of the

invention, disclosing said oil burner control as when applied to use, the section being taken on line 1—1 in Fig. 3;

Fig. 2 is a detail sectional view of the stack 5 thermostat of the oil burner control, taken as on line 2—2 in Fig. 1;

Fig. 3 is an elevational view of the oil burner control with cover removed, as seen from the right in Fig. 1;

Fig. 4 is a vertical sectional view taken as on 10 line 4—4 in Fig. 5;

Fig. 5 is a vertical sectional view taken on line 5—5 in Fig. 3;

Fig. 6 is a vertical sectional view taken as on 15 line 6—6 in Fig. 5;

Fig. 7 is a detail sectional view taken as on line 7—7 in Fig. 4;

Fig. 8 is a horizontal sectional view taken on line 8—8 in Fig. 3;

Fig. 9 is a detail sectional view taken on line 20 9—9 in Fig. 3; and

Fig. 10 is a diagrammatic view disclosing the wiring system of the oil burner control.

With respect to Fig. 10 of the drawings and the numerals of reference thereon, 15 represents 25 the ignition device, 16 the motor, and 17 the solenoid for actuating the control valve of an oil burner. The major portion of the improved control for said oil burner, indicated generally at 18, is shown applied to the stack 19 of an ordinary or preferred type of oil burner furnace (not shown). See Fig. 1 in connection with Fig. 10.

Any ordinary thermostatic element 20, in remote relation to the oil burner furnace, as, for instance, in a room to be heated, constitutes 35 means for actuating an electric switch 21, as disclosed a thermal electric switch, for the ignition device 15. The electric switch 21, actuated by the thermostatic element 20, cooperates with 40 said thermostatic element to control circuits, in a manner to be set forth, including said electric switch 21 and a second electric switch 22, as disclosed also a thermal electric switch, for the motor 16 and the control valve 17. The electric 45 switches 21 and 22 are electrically connected and said electric switch 22 itself cooperates with the thermostatic element 20, in a manner also to be set forth, to control a circuit through said electric switch 22. See Figs. 4, 5 and 10.

The oil burner control also includes a stack 50 thermostat 23 which manipulates, in a manner to be made clear, additional electric switches in the circuits having the thermal electric switches 55

21 and 22, and said oil burner control desirably also includes a safety electric switch 24 which is connected in series with said switches 21 and 22 and is associated with the thermal electric switch 21 in a novel and improved manner to be set forth.

The stack thermostat 23 is mounted directly in the furnace stack 19, and the thermal switches 21 and 22, safety switch 24, and additional switches of the oil burner control in the circuits having said switches 21, 22 and 24 are mounted in a casing 25 adjacent said stack 19 at the outside thereof, as shown more clearly in Fig. 1. As disclosed, the stack 19 includes an opening 26, and a bracket 27 is permanently attached to said stack, as at 28, about said opening, the bracket having a desirably horizontally disposed hollow neck 29 which extends outwardly from the stack. A hollow standard or carrying member 30, slidably received in the neck 29, rigidly supports, as at 31, the legs of a U-bracket 32, and rigidly supports, as at 33, an insulating panel 34, which may desirably be composed of asbestos, or other suitable material. The U-bracket 32 in turn supports a stack thermostatic element 35, and the panel 34 in turn supports the casing 25. The supporting or carrying member 30 may include air openings as shown.

The thermostatic element 35 is of the peculiar construction as best shown in Figs. 1 and 2, including a plurality of reversely positioned U-members 36 adjacent legs of which are welded or otherwise secured together as at 37. Each U-member 36 is a bi-metallic strip, and a leg of an outermost U-member, at the left in Fig. 1, is attached, as at 38, to the base 39 of the U-bracket 32. A leg of the opposite outermost U-member 36, at the right in said Fig. 1, is attached, as at 40, to a rod 41, which may desirably be square in cross-section. The arrangement is such that the rod 41 extends horizontally out of the stack and into the casing 25, and said rod may have free sliding fit in circular openings, designated 42 and 43, in the base 44 of the standard or member 30 and in the panel 34, respectively. The arrangement as disclosed is such that when the thermostatic element 35 is heated, the legs of each U-member 36 thereof move toward each other, to cause the rod 41 to move inwardly of the stack 50 and inwardly of the casing 25, and when said element 35 is cooled, said legs of each U-member move apart, to cause said rod 41 to move outwardly of said stack and outwardly of said casing, as will be understood.

As is evident, the unit including the member 30, the stack thermostat, the panel 34, the casing 25, etc., is very easily and conveniently insertable in and removable from the stack through the hollow neck 29. As illustrated in Fig. 1, the standard or carrying member 30 may have its position fixed when inserted into the stack by means of a set screw 45.

The casing 25 is supported upon the panel 34, in spaced relation thereto, by headed and nutted bolts 46 which pass through said panel and the base 47 of said casing and through spacing blocks or members 48 therebetween.

A transformer 49, for a purpose to be set forth, is suitably carried by the casing 25, and said base 70 47 of said casing conveniently supports an insulating panel 50, which may desirably consist of bakelite, or other suitable material. As illustrated, the panel 50 is supported upon the base 47 of the casing, in spaced relation thereto, by 75 headed and nutted bolts 51 which pass through

said panel 50 and base 47 and through spacing blocks or members 52 therebetween.

The panel 50 also includes a circular opening, designated 53, in which the rod 41 freely slides, said rod having its end opposite the thermostatic element 35 terminating adjacent the cover 54 of the casing 25. Said cover 54 is removably attached to the casing, as by screws 55.

It will be seen that the circular openings 42, 43 and 53, or any one of said openings, provide a four point, or two point, bearing for the squared rod 41. Also, it is evident that said rod does not turn as it is moved longitudinally or inwardly and outwardly by the thermostatic element 35, but always moves horizontally without any tendency toward transverse rocking. Friction upon the rod is thus kept at a minimum at location or locations where said rod is slidably mounted. And furthermore, it will be seen, the thermostatic element 35, while contracting with heat to have tendency to keep out soot, is wide open to passage of gases through it, and heat changes work said thermostatic element to cause it to have tendency to remove soot, etc., especially when the U-members 36 are disposed so that the widths of the legs thereof are vertical.

The outer portion of the rod 41 is desirably I-shape in cross-section, including an upper horizontal portion 56 and a lower horizontal portion 57. The portion 56 slidably carries a U-clip 58, and the portion 57 slidably carries a U-clip 59. Flanges 60 on said U-clips 58 and 59 retain the U-clips upon the portions 56 and 57, and a small flat spring 61 between each U-clip and its corresponding portion 56 or 57, as the case may be, frictionally retains each said U-clip against tendency toward sliding movement upon the rod 41. See Figs. 1, 3, 4, 8, 9 and 10.

The insulating panel 50 rigidly supports, as at 62, a conducting plate 63, and said plate 63 conductively carries, as at 64 and 65, respectively, a pair of movable switch elements denoted 66 and 67. Said movable switch elements 66 and 67 are adapted to engage stationary switch elements designated 68 and 69, respectively, insulatively mounted, as at 70 and 71, upon a bracket 78 suitably attached to the panel 50. The conducting plate 63 insulatively carries, as at 72, a movable switch element 73 having a conducting boss 74 adapted to engage a conducting boss 75 upon the movable switch element 66 and to be actuated to cause said movable switch element 66 to be removed from the stationary switch element 68.

A stop member 76, insulatively mounted as at 77 upon the bracket 78 carried by the insulating panel 50 for adjustment longitudinally of the rod 41, limits inward movement of the U-clip 58, said U-clip including an extension portion 79 adapted to engage said stop member 76. Outward movement of the U-clip 58 is limited by engagement of said extension portion 79 with the movable switch element 67 when itself engaged with the stationary switch element 69. It should be remarked that the movable switch element 67 is of resilient structure and removes itself from the stationary switch element 69 except when said switch elements are held in engagement by the extension portion 79 of the U-clip 58. See Figs. 1, 9 and 10. A stop member 80, insulatively mounted as at 81 upon the bracket 78 for adjustment longitudinally of the rod 41, limits outward movement of the U-clip 59, said U-clip including an extension portion 82 adapted to engage said stop member 80. Inward movement of the U-clip 59 causes the extension portion 82 to engage the

movable switch element 73. Said movable switch element 73 is of resilient construction and is in open position when the oil burner furnace is cold, while the switch elements 66 and 68 are, 5 when said furnace is cold, engaged with each other, as disclosed in Figs. 8 and 10. The arrangement is such that inward travel of the U-clip 59 first causes the conductive bosses 74 and 75 upon the movable switch elements 73 and 66, 10 respectively, to engage each other, and said movable switch element 66 to later be removed from the stationary switch element 68.

The drawings disclose the various parts of the oil burner control positioned as when the oil burner is inactive or extinguished and the space to be heated is at desired temperature. At this time, the thermostatic element 35 has its greatest expansion, assuming the stack 19 is at minimum temperature, so that the rod 41 is at the limit of 15 its outward movement, to cause the extension 79 upon the U-clip 58 to engage the movable switch element 67 and hold it against the stationary switch element 69, and to cause the extension 82 upon the U-clip 59 to engage the stop 80. Speaking generally, when the space to be heated calls for heat, the ignition of the oil burner is effected, and immediately the stack 19 begins to warm up. This causes the thermostatic element 35 to commence to contract. Almost immediately the extension 30 79 upon the U-clip 58 is withdrawn from the movable switch element 67 to allow said element to resiliently remove itself from the stationary switch element 69. Soon thereafter, upon further inward movement of the rod 41, the extension 79 upon the U-clip 58 engages the stop 76 to be there arrested, before said rod 41 reaches the limit of its inward movement. After the extension 79 engages the stop 76 upon inward movement of the rod 41, said rod slides relatively to 40 the clip 58 during the further inward movement of the rod. When then the space to be heated ceases to call for heat and the oil burner is extinguished, as will be fully explained, the thermostatic element 35 commences to expand at the 45 moment the stack 19 commences to cool down, and the rod 41 simultaneously commences to move outwardly, carrying with it the U-clip 58 and its extension 79. Thus it will be seen that the exact time of engagement of the switch elements 67 and 69 with each other upon the cooling 50 down of the furnace can be nicely regulated by the original setting of the stop 76. Also, when the oil burner is ignited as before stated to warm the stack and thus cause the thermostatic element 35 to commence to contract, the extension 82 upon the U-clip 59 moves inwardly from the stop 80, and thereafter, upon further inward movement of the rod 41, said extension 82 engages the movable switch element 73 and causes the 55 boss 74 thereon to engage the boss 75 upon the movable switch element 66. As the rod 41 then moves still further inwardly, the movable switch element 66 is removed from the stationary switch element 68, through the instrumentality of the 60 engaging bosses 74 and 75. As before mentioned, both of said bosses are contact or conducting members. Thereafter, when the burner is extinguished, as above mentioned, and the thermostatic element expands with the cooling down of 65 the stack to cause the rod 41 to move outwardly, the clip 59 with extension portion 82 simultaneously moves outwardly, first allowing the movable switch element 66 to engage the stationary switch element 68 and then allowing the resilient switch 70 element 73 to remove its boss or contact 74 from

the boss or contact 75 upon the movable and resilient switch element 66. Upon further outward movement of the rod 41 with the cooling of the stack, the extension 82 engages the stop 80, before said rod 41 reaches the limit of its outward movement, and thereafter as said rod 41 moves still further outwardly, it slides relatively to the U-clip 59. When then the space to be heated later calls for heat and the oil burner is ignited to cause the stack to heat up and the thermostatic element 35 to a result commence to contract, the rod 41 simultaneously commences to move inwardly, carrying with it the U-clip 59 and its extension 82. Thus the exact time of engagement of the switch elements 73 and 66 and the 15 disengagement of the switch elements 66 and 68 upon the heating up of the furnace can be nicely regulated by the original setting of the stop 80.

The structure of the thermal electric switch 21 for the ignition device 15 is best disclosed in Figs. 1, 3, 4, 5, 7, 8 and 10. As there shown, a resistor 83 desirably consists of a single strand of suitable wire of relatively fine dimension having its end portions attached to terminals, designated 84 and 85, respectively, mounted upon an insulating block 86 itself conveniently carried, as by a bracket 87, upon the insulating panel 50. The intermediate portion of the wire resistor 83 extends back and forth across the outer face of an insulating block 88, desirably of lava, and outer parts of said intermediate portion of the wire strand 83, in spaced relation to the terminals 84 and 85, are rigidly attached to an outer portion of said insulating or lava block 88, while inner parts of said intermediate portion are rigidly attached to said insulating block 86, between the terminals 84 and 85. More specifically, the insulating block 86 supports a series of alining, spaced apart lugs or posts 89, and the insulating block or lava 88 supports a similar series of alining, spaced apart lugs or posts 90, about all of which lugs or posts 89 and 90 the wire strand 83 is successively wound. In the manufacture of the thermal electric switch 21, an end of the wire strand resistor 83 thereof may be first attached 45 to a terminal 84 or 85, an adjacent portion of said wire strand may then be wound one or more times about an outermost lug or post 89, then the next adjacent portion of the wire strand may be wound about an outermost lug or post 90, 50 then about the lug or post 89 next adjacent one already wired, then about the lug or post 90 next adjacent one already wired, and so on, until the lugs or posts are all wired, and finally the wire strand may be attached to the terminal 85 or 55 84. If desired, after the lugs or posts are all wired, a touch of cement may be applied, as at 91 in Figs. 4 and 5, back of each lug or post, to insure that the wire cannot become accidentally removed from the lugs or posts. One end portion of the block or lava 88 is conveniently pivoted to the bracket 87, as by a small shaft 92 which passes through ears upon said block or lava 88 disposed between flanges of said bracket. A coil spring 93, attached to the bracket 87 at 65 94 and to the inner face of the block or lava 88 at 95, urges said block or lava 88 to swing on its axis toward the insulating panel 50. Each length of the wire resistor 83 is taut or tensioned between the lugs or posts 89 and 90 to normally hold 70 the block or lava 88, against the action of the coil spring 93, at its farthest distance from the panel 50, and so that the blocks 86 and 88 will desirably be in approximate alinement. And the wire strand resistor 83, which is obviously non- 75

inductive, is composed of material having a coefficient of expansion sufficiently great to cause immediate lengthening of said wire strand resistor to an extent to allow movable contact elements upon the block or lava 88 to make electrical engagement with stationary contact elements upon the insulating panel 50 immediately when only a very small current of electricity is applied to said resistor 83 in a manner to be explained.

5 As disclosed, the insulating panel 50 suitably supports a stationary contact strip 96 and a stationary contact plate 97, while the block or lava 88 has a shaft 98 extending longitudinally from the free end thereof, upon which shaft 98 the intermediate portion of a double contact element 99 is rotatably mounted. Said shaft 98 carries a coil spring 100 one end 101 of which engages a contact element 99 and the other end 102 of which engages the block or lava 88 to hold a contactor 103 of said element 99 in engagement with the plate 97 and another contactor 104 of said element out of engagement with the strip 96. See Figs. 3, 4, 5 and 8. Evidently, when the resistor 83 becomes lengthened, the coil spring 93 10 acts against the tendency of the weaker coil spring 100 to cause the contactor 104 to engage the contact strip 96. Also, the insulating panel 50 suitably supports a pair of spaced apart screw contacts, denoted 105 and 106, respectively, which 15 screw contacts extend from said panel 50 into cut-out portions 107 and 108 of the block or lava 88. Said member 88 carries spring clip contacts, denoted 109 and 110, respectively, the former being adapted to engage the contact 105 and the latter being adapted to engage the contact 106 20 when the resistor 83 is energized in the manner to be set forth.

30 The structure of the thermal electric switch 22 for the motor 16 and the control valve 17 is best disclosed in Figs. 3, 4, 8 and 10. As there shown, a resistor 111 desirably consists of a single strand of suitable wire, similar to the wire of the strand 83, having its end portions attached to terminals, designated 112 and 113, respectively, 35 mounted upon an insulating block 114, similar to the block 86, itself conveniently carried, as by a bracket 115, upon the insulating panel 50. The intermediate portion of the wire resistor 111 extends back and forth across the outer face of an insulating block 116, also desirably of lava, and outer parts of said intermediate portion of the wire strand 111, in spaced relation to the terminals 112 and 113, are rigidly attached to an outer portion of said insulating or lava block 116, while 40 inner parts of said intermediate portion are rigidly attached to said insulating block 114, between the terminals 112 and 113. More specifically, the insulating block 114 supports a series of alining, spaced apart lugs or posts 117, and the insulating block or lava 116 supports a similar series of alining, spaced apart lugs or posts 118, about all of which lugs or posts 117 and 118 the wire strand 111 is successively wound. In the manufacture of the thermal electric switch 22, an end of the 45 wire strand resistor 111 thereof may be first attached to a terminal 112 or 113, an adjacent portion of said wire strand may then be wound one or more times about an outermost lug or post 117, then the next adjacent portion of the wire 50 strand may be wound about an outermost lug or post 118, then about the lug or post 117 next adjacent one already wired, then about the lug or post 118 next adjacent one already wired, and so on until the lugs or posts are all wired, and 55 finally the wire strand may be attached to the

terminal 113 or 112. If desired, after the lugs or posts are all wired, a touch of cement may be applied, as at 119 in Fig. 4, back of each lug or post, to insure that the wire cannot become accidentally removed from the lugs or posts. One 5 end portion of the block or lava 116 is conveniently pivoted to the bracket 115, as by a small shaft 120 which passes through ears upon said block or lava 116 disposed between flanges of said bracket. A coil spring 121, attached to the 10 bracket 115 and to the inner face of the block or lava 116, urges said block or lava 116 to swing on its axis toward the insulating panel 50. Each length of the wire resistor 111 is taut or tensioned between the lugs or posts 117 and 118 to 15 normally hold the block or lava 116, against the action of the coil spring 121, at its farthest distance from the panel 50, and so that the blocks 114 and 116 will desirably be in approximate alinement. The wire strand resistor 111 may desirably be composed of the same material as is the wire strand resistor 83 to cause immediate lengthening thereof to allow movable contact elements upon the block or lava 116 to make electrical engagement with stationary contact elements upon the insulating panel 50 immediately when a small current of electricity is applied to 20 said resistor 111 in a manner also to be explained. As disclosed, the insulating panel 50 suitably supports a stationary contact strip 122, and the 25 block or lava 116 has a shaft 123 extending longitudinally from the free end thereof, upon which shaft 123 the intermediate portion of a contact element 124 is rotatably mounted. Said shaft 123 carries a coil spring 125 one end 126 of which 30 engages the contact element 124 and the other end 127 of which engages the block or lava 116 to hold a contactor 128 of said element 124 in engagement with the plate 122 and another contactor 129 of said element out of engagement with the plate 97. 35 See Figs. 3, 4 and 8. Evidently, when the resistor 111 becomes lengthened, the coil spring 121 acts against the tendency of the weaker coil spring 125 to cause the contactor 129 to engage the contact plate 97. Also, the insulating panel 50 suitably supports a screw contact 130 which extends from said panel 50 into a cut-out portion 131 of the block or lava 116. Said member 116 carries a spring contact clip 132 which is adapted to engage the contact 130 when the resistor 111 is energized in the manner to be set forth.

The structure of the safety electric switch 24 and its manner of association with the thermal electric switch 21 is best disclosed in Figs. 1, 3, 5, 6, 7, 8 and 10. As there shown, a bracket 55 133, attached to the bracket 87 as at 134, rigidly carries one end of a bi-metallic strip 135 which is in proximate, superimposed relation to the resistor 83 to receive heat from said resistor when it is energized. The body of the bi-metallic strip 60 135 lies adjacent an opening 136 in said bracket 133 so as to be freely movable toward and away from said resistor 83. An extension 137 of the bracket 133, at the end thereof to which the bi-metallic strip 135 is secured, rigidly supports, as at 138, one 65 end portion of a switch carrying member 139. The opposite end portion of said switch carrying member 139 may be fixed in spaced relation to the body of the bracket 133 in any convenient manner, as by a small bolt 140 including a nut 141 thereon engaging said bracket 133 and nuts 142 on said bolt engaging opposite surfaces of said switch carrying member 139. A ledge or flange 143 upon the member 139, between said member and the bi-metallic strip 135, rigidly sup- 70 75

ports, as at 144, a contact carrying member 145, which is desirably parallel with and in spaced relation to both the member 139 and the bimetallic strip 135. Numeral 146 designates a stationary contact element insulatively carried by the member 145. A movable and resilient contact element 147 is insulatively attached to the ledge or flange 143 and the member 145 at 144. Numeral 148, Fig. 10, represents a terminal for the element 147. Said contact element 147 is of structure to spring away from the fixed contact element 146 except when held in engagement therewith as follows. The end of the member 145 opposite the ledge or flange 143 hingedly supports, as at 149, an L-lever 150, the axis of said lever being arranged in the shorter leg 151 thereof. The longer leg 152 of said L-lever extends to position over the movable and resilient contact element 147, and conveniently carries, as at 153, an insulating strip 154 arranged against the inner surface of said longer leg and adapted to engage said contact element 147. The bi-metallic strip 135 includes an oblique extension 155 which normally engages the lower portion of the inner surface of the shorter leg 151 of the L-lever to hold the insulating strip 154 against the movable and resilient contact element 147 and to in turn hold said element 147 in engagement with the stationary contact element 146. The arrangement is such that when the bi-metallic strip 135 warps in direction toward the resistor 83, due to the reception of sufficient heat by said bi-metallic strip from said resistor, the oblique extension 155 is removed from the free end of the shorter leg 151 to thus allow the movable and resilient contact element 147 to spring away from the stationary contact element and cause the longer leg 152 to move outwardly and the shorter leg 151 to move inwardly. Thereafter, even when the bi-metallic strip 135 cools down, the contact elements 147 and 146 will remain separated. To again bring said contact elements 147 and 146 together, and thus re-set the safety switch, it is necessary to manually depress a push button 156, arranged in the carrying member 139, against the action of the movable and resilient contact element 147. Obviously, depression of said push button 156 swings the L-lever 150 on its axis 149, moving the longer leg 152 inwardly and the shorter leg 151 outwardly, past the oblique extension 155 to position where the inner surface of said shorter leg is again engaged by said oblique extension of the bi-metallic strip 135, as shown very clearly in Fig. 5, of course when said bi-metallic strip is sufficiently unheated to be thus normally positioned.

The stationary contact plate 97 carries a terminal 157 receiving an incoming line wire 158. The insulating panel 50 conveniently supports, as by a metallic strip 159 thereon, a terminal 160 receiving an incoming line wire 161.

A lead wire 162 connects the stationary contact plate 97 with one side of the primary of the transformer 49, and a lead wire 163 connects the terminal 160 with the opposite side of said primary.

A lead wire 164 connects the terminal 160 with the ignition device 15, the motor 16 and the control valve 17. A lead wire 165 connects said ignition device with a terminal 166 carried by the stationary contact strip 96. A lead wire 167 connects said motor 16 with a terminal 168 carried by the stationary contact strip 122, and a lead wire 169 connects said control valve 17 with said terminal 168.

The conducting plate 63 insulatively carries a

terminal 170, and conductively carries a terminal 171.

A lead wire 172 connects one side of the secondary of the transformer 49 with the terminal 170, and a lead wire 173 connects said terminal 170 with the movable contact element 20 of the room thermostat. A lead wire 174 connects the terminal 171 with the stationary contact element 175 of said room thermostat.

A lead wire 176 connects the conducting plate 63 with the screw contact 105. A lead wire 177 connects the stationary switch element 68 with the screw contact 106. A lead wire 178 connects the stationary switch element 69 with the spring clip 110. A lead wire 179 connects the spring clip 109 with the spring clip 132. A lead wire 180 connects the movable switch element 73 with the screw contact 130.

A lead wire 181 connects the lead wire 178 with the terminal 85, and a lead wire 182 connects the terminal 84 with a lead wire 183 attached at one of its ends to the stationary contact element 146 and at its other end to the terminal 113. A lead wire 184 connects the terminal 112 with the lead wire 179. And a lead wire 185 connects the movable and resilient contact element 147 with the side of the secondary of the transformer opposite the side to which the lead wire 172 is attached.

The manner in which the oil burner control operates will now be described. In Fig. 10 all of the parts of the apparatus are disclosed in position as when the oil burner is extinguished and the temperature of the space to be heated is the desired temperature. When the temperature of said space to be heated falls below said desired temperature, the movable contact element 20 of the room thermostat engages the stationary contact element 175 thereof. The contact elements 67 and 69 being in engagement, a circuit is completed through the resistor 83 immediately upon engagement of the contact elements 20 and 175 with each other, said circuit being traced from the secondary of the transformer through the lead wire 172 to the terminal 170, thence through the lead wire 173 to the bi-metallic strip 20, thence through the stationary contact element 175 and the lead wire 174 to the terminal 171, thence through the conducting plate 63 to the movable contact element 67, thence through the stationary contact element 69 and the lead wires 178 and 181 to the terminal 85, thence through the resistor 83, the terminal 84, and the lead wires 182 and 183 to the stationary contact element 146, and thence through the movable and resilient contact element 147 and the lead wire 185 back to the secondary of the transformer. Energization of the resistor 83 causes its wire strand to be lengthened, as already stated, to allow the coil spring 93 to swing the block or lava 88 upon its axis and cause the contact elements 104, 96 and 109, 105 and 110, 106, respectively, to come into engagement. Thus a holding circuit through the resistor 83 is established, said holding circuit being traced from the secondary of the transformer 49 through the lead wire 172 to the terminal 170, thence through the lead wire 173 to the element 20, thence through the element 175 and the lead wire 174 to the terminal 171, thence through the conducting plate 63 to the movable contact element 66, thence through the stationary contact element 68 engaged with said element 66, thence through the lead wire 177 to the screw contact 106, thence through the spring clip 110 to the lead wire 181, thence through the terminal 85, the resistor 83 and the terminal 84 to the lead wire 75

182, and thence through the lead wire 183, the contact elements 146 and 147 and the lead wire 185 back to the secondary of the transformer. It will be apparent that the holding circuit just described will remain made until later broken at the contact elements 66 and 68. Also, when the resistor 83 is energized to cause the contact elements 104 and 96 to engage each other, a circuit is completed through the ignition device 15, said 5 circuit being traced from the line wire 158 through the terminal 157 and the stationary contact plate 97 to the contactor 103 of the contact element 99, thence through the contactor 104 to the contact strip 96, thence through the terminal 166 and the 10 lead wire 165 to the ignition device 15, and thence through the lead wire 164 and the terminal 160 to the line wire 161. The circuit through said ignition device 15 will remain made so long as the resistor 83 is energized. And when the resistor 83 15 is energized to cause the contact elements 109 and 105 to engage each other, a circuit is completed through the resistor 111, said circuit being traced from the secondary of the transformer 49 through the lead wire 172 to the terminal 170, thence 20 through the lead wire 173 to the element 20, thence through the element 175 and the lead wire 174 to the terminal 171, thence through the conducting plate 63 and the lead wire 176 to the screw contact 105, thence through the spring clip 109 25 and the lead wire 179 to the lead wire 184, thence through the terminal 112, the resistor 111 and the terminal 113 to the lead wire 183, and thence through the contact elements 146 and 147 and the lead wire 185 back to the secondary of the 30 transformer. Thus the resistor 111 when once energized will obviously remain energized at least until the contact elements 66 and 68 are separated to break the holding circuit for the resistor 83. Energization of the resistor 111 causes its wire 35 strand to be lengthened, as already stated, to allow the coil spring 121 to swing the block or lava 116 upon its axis and cause the contact elements 129, 97 and 132, 130, respectively, to come into engagement. When the contact elements 129 and 97 40 engage each other, a circuit is completed through the motor 16, as well as through the control valve 17, said circuit being traced from the line wire 158 through the terminal 157 and the stationary contact plate 97 to the contactor 129 of the contact element 124, thence through the contactor 45 128 and the stationary contact strip 122 to the terminal 168, thence through the lead wire 167 to the motor 16 and through the lead wire 169 to the control valve 17, and thence through the lead wire 164 and the terminal 160 to the line 50 wire 161.

It will now be evident that upon engagement of the contact elements 20 and 175 of the room thermostat, the ignition device 15, the motor 16 and the control valve 17 will each be energized and thus set in operation to perform its ordinary service. For some reason or other, the ignition device 15 may fail to properly function. That is, said ignition device may fail to ignite the fuel fed to the burner by the motor 16 through an orifice which may be controlled by a valve such as 17, or the fuel feed may fail. In the event of no combustion occurring in the burner due to failure of ignition, the contact elements 66 and 68, controlling the holding circuit for the resistor 83 as already stated, will remain in engagement due to the fact that said contact elements 66 and 68 are caused to be separated only by a rise in temperature in the stack 19. Eventually then, because of energization of the resistor 55

83 for an undue length of time, the bi-metallic strip 135 will absorb sufficient heat from said resistor 83 to separate the contact elements 146 and 147 in the manner as already explained. Thus both of the resistors 83 and 111 will be de-energized, and the apparatus will be rendered inoperative and can be reset only by manually depressing the button 156 as before mentioned. When said ignition device functions to cause combustion to occur in the burner, the stack 19, naturally, immediately commences to heat up, and the thermostatic element 35 simultaneously contracts to move the rod 41 inwardly of the stack. The U-clip 59 with its extension portion 82 moves inwardly with said rod, and said extension portion 82 engages the movable switch element 73 to cause the conducting boss 74 thereon to engage the conducting boss 75 upon the movable switch element 66. A holding circuit is thus made through the resistor 111, to be effective in keeping 20 said resistor 111 energized when the resistor 83 is de-energized (to break the switch 109, 105 in the circuit before made through the resistor 111) by later separation of the contact elements 66 and 68 in the holding circuit for said resistor 83. Said 25 contact elements 66 and 68 are separated, as hereinbefore set forth, by further inward movement of the rod 41, through the instrumentality of the extension portion 82 pushing against the switch element 73 which in turn pushes by its 30 35 boss 74 against the boss 75 upon the switch element 66. Obviously, de-energization of the resistor 83 separates the contact elements 104 and 96 and breaks the ignition device circuit to render the ignition device inoperative. As before mentioned, as soon as the rod 41 starts to move inwardly, the extension portion 79 upon the U-clip 58 releases the movable switch element 67 and this springs away from the stationary switch element 69, so that the circuit through the resistor 40 45 50 55 60 65 70 75 80 85 90 95 100 105 110 115 120 125 130 135 140 145 150 155 160 165 170 175 180 185 190 195 200 205 210 215 220 225 230 235 the circuit through the motor 16 and the control valve 17, and said motor becomes inoperative and said valve shuts off. Thus the oil burner is extinguished and the stack starts to cool down. 5 Upon inward movement of the rod 41, the U-clip 58 with extension portion 79 was arrested by the stop member 76. When the oil burner is extinguished, said rod 41 commences to move outwardly as already described. During the outward 10 movement of the rod 41, the extension portion 79 engages the contact element 67 and causes this to engage the contact element 69, while the extension portion 82 releases the switch elements 66 and 73 and engages the stop member 80. Upon 15 being released by said extension portion 82, the switch element 66 first engages the switch element 68, and the boss 74 upon the switch element 73 later becomes removed from the boss 75 upon the switch element 66. Thus the parts of the apparatus 20 are returned to their normal positions, as shown in Fig. 10, ready to again operate in the manner as explained when the room thermostat again closes as the space to be heated calls for heat.

25 In Figs. 1, 3, 4, and 5, numeral 186 represents an insulating plate which separates the terminals 168, 157, 160 and 166, having connection with the line wires 158 and 161, from the remainder of the parts in the casing 25. Said insulating plate 30 186 is supported, as at 187, by an offset portion 188 of the stationary contact plate 97.

Attention is called to the fact that the contactors 128, 129 and 103, 104 of the contact elements 124 and 99, respectively, and the plate 97 35 and the strips 96 and 122 which said contact elements engage, are all adapted to be conductively connected in circuits including the line wires 158 and 161. Thus there may at times be a tendency for the elements 129, 97 and 104, 96, respectively, 40 to stick together, due to a certain amount of arcing at said elements caused by the current of relatively high voltage from the line wires. In case there is such tendency toward sticking together of said elements 129, 97 and 104, 96 when 45 the insulating blocks 116 and 88 swing in direction away from the insulating panel 50, the contactors 128 and 103 of the contact elements 124 and 99, respectively, will, obviously, be easily and readily removed from the strip 122 and the plate 50 97, to positively break the corresponding circuits, and a rocking action will as a result of the removal of said contactors 128 and 103 be imparted to said contact elements 124 and 99, which rocking action will cause the contactors 129 and 104 55 to have a rocking or rolling action tending to remove said contactors from the plate 97 and the strip 96, rather than a direct lifting movement as would be the case were the special type of contact elements 124 and 99 as illustrated and 60 described not employed.

Desirably, a permanent magnet 189 is situated adjacent to the movable contact element 20 of the room thermostat. The function of said magnet 189 is to firmly hold the contact elements 20 and 175 in engagement when once together, and thus provide a regulatable differential for the smooth and proper operation of the oil burner control. That is to say, were the permanent magnet 189, or equivalent, not employed, there 70 would be tendency for the elements 20 and 175 to separate too quickly upon elevation of the temperature of the space being heated. Also, said magnet 189 evidently provides for a quick and snappy make and break of the switch of 75 the room thermostat.

The thermal electric switches 21 and 22 and the safety electric switch 24 are adapted to be connected in circuits of relatively low voltage, including the stepped-down secondary of the transformer 49. The employment of thermal electric switches, such as 21 and 22, which are directly responsive in their operation to expanding and contracting actions of resistors, such as 83 and 111, which resistors expand and contract immediately upon receiving flow of relatively 10 light current, makes provision for efficient and effectual operation of the various electric switches manipulated by the thermal electric switches 21 and 22 practically instantaneously with the opening and closing of the circuits controlling said 15 thermal electric switches. Inasmuch as the resistors 83 and 111 are non-inductive, the room thermostat and the other electric switches of the oil burner control in circuit with the secondary 20 of the transformer can incorporate very delicate 25 and fine electrical contacts. In practice, the operating power required by the resistors 83 and 111 does not have to exceed a very few watts, which, flowing through a non-inductive circuit, causes practically no arcing at the room thermostat contacts, or at the other contacts in circuits including the secondary of the transformer.

The oil burner control of the invention will evidently function to care for each and all of the heating problems which may present themselves. Upon failure of ignition, the safety electric switch will be surely and positively operated to render the ignition device and the fuel forcing motor inoperative and to break the circuit through the means operating the control valve, thus insuring that said valve will automatically close. Upon the flame becoming extinguished for any reason before the space being heated is satisfied to break the circuit at 20 and 175, the parts of the oil burner control will all automatically return to normal positions as in Fig. 10, and immediately the resistors 83 and 111 will be energized, as already set forth, to thereafter cause either proper ignition and combustion to occur, 35 provided the trouble was temporary, or the safety switch to be broken, provided the trouble is not temporary and some adjustment of the fuel feed or other part of the oil burner proper is required. 40

The novel and improved oil burner control includes an ordinary room thermostat consisting 50 of a single bi-metallic strip or blade, which necessitates the employment of only a quite simple wiring system or arrangement as illustrated and described.

55 What is claimed is:

1. A control system, for a burner having electrically actuated fuel feeding and ignition means, comprising a main control switch, a combustion responsive switching mechanism having first and second contacts which are closed in the absence of combustion and are successively opened upon the establishment of combustion, and third contacts which are open in the absence of combustion and closed upon the establishment of combustion prior to the opening of the second contacts, a first multiple contact relay operable when energized to close the circuit of the fuel feeding means and a holding circuit through its actuating means including said third contacts, a circuit for energizing the first relay actuating means, a second multiple contact relay including an actuating means operable when energized in response to the closing of the main control switch and said first contacts to successively close the circuit of the ignition means and the circuit for energizing 70 75

the first relay actuating means, and a circuit including the second relay actuating means and said second contacts for maintaining energization of said second relay actuating means until said 5 third contacts are closed.

2. A control system, for a burner having electrically actuated fuel feeding and ignition means, comprising a main control switch, a combustion responsive switching mechanism having first and 10 second contacts which are closed in the absence of combustion and are successively opened upon the establishment of combustion, and third contacts which are open in the absence of combustion and are closed upon the establishment of 15 combustion prior to the opening of the second contacts, a first multiple contact relay operable when energized to close the circuit of the fuel feeding means and a holding circuit through its actuating means including said third contacts, a 20 circuit for energizing the first relay actuating means, a second multiple contact relay including an actuating means constituted as a thermal device operable when energized in response to the closing of the main control switch and said first 25 contacts to successively close the circuit of the ignition means and the circuit for energizing the first relay actuating means, a circuit including the second relay actuating means and said second contacts for maintaining energization of said 30 second relay thermal device actuating means until said third contacts are closed, and a ther-

mostatic safety switch responsive in its operation to the absorption of heat from said thermal device actuating means controlling energization of said thermal device.

3. A control system, for a burner having electrically actuated fuel feeding and ignition means, comprising a main control switch, a combustion responsive switching mechanism having first and second contacts which are closed in the absence of combustion and are successively opened upon 10 the establishment of combustion, and third contacts which are open in the absence of combustion and are closed upon the establishment of combustion prior to the opening of the second contacts, a first multiple contact relay operable when energized to close the circuit of the fuel feeding means and a holding circuit through its actuating means including said third contacts, a circuit for energizing the first relay actuating means, a second multiple contact relay including 15 an actuating means operable when energized in response to the closing of the main control switch and said first contacts to successively close the circuit of the ignition means and the circuit for energizing the first relay actuating means, and a thermostatic safety switch, controlling energization of the system and rendered operative to open by a prolonged absorption of heat from the actuating means for said second relay. 20
